LIGHT SIGNAL

George R. Pflasterer, Greenville, Pa., assignor to
The Union Switch and Signal Company, Swiss-
vale, Pa., a corporation of Pennsylvania

Application October 28, 1942, Serial No. 463,658

5 Claims. (Cl. 177—327)

My invention relates to light signals, and has particular reference to light signals of the searchlight type incorporating means for projecting a plurality of differently colored indications from an optical system employing a single source of light. More particularly, my invention relates to the provision of novel and improved means in such signals for projecting a plurality of differently colored indications having relative intensities independent of the coefficients of transmission of the colored filters employed to provide the different indications.

A searchlight type signal comprises an optical unit which has a single lamp as a source of light, and an operating mechanism for selectively interposing one or another of a plurality of colored filters in the beam projected by the optical unit. In accordance with the standard practice in railway signaling, three filters comprising a red, a yellow and a green filter are employed in order to obtain a red, a yellow and a green indication, respectively. Although the same optical system having a source of uniform intensity is employed to project all of the indications, the indications are not of equal intensities due to the fact that the filters have different coefficients of transmission. That is, when filters of the standard colors adapted for railway use are employed, the amount of available light transmitted by the filters is of the order of 7% for the red filter, 12% for the green filter and 25% for the yellow filter. This of course causes the intensities of the indications to be dependent upon the coefficients of transmission of the filters employed and results in a marked difference in brightness between the indications, particularly the yellow and red indications.

In view of the above-mentioned and other important considerations, it is an object of my invention to provide novel and improved means in searchlight type signals for projecting indications that have substantially uniform intensities.

Another object is to provide novel and improved means for varying the intensity of the light source of a searchlight signal to compensate for the different coefficients of transmission of the filters employed, whereby to obtain a plurality of different colored beams having relative intensities independent of the ratio of the coefficients of transmission of the color filters interposed in such beams.

An additional object is the provision of novel and improved means in a searchlight type signal for varying the intensities of the beams projected thereby.

In practicing the invention, the above-mentioned and other important objects and characteristic features which will become readily apparent from the following description, are attained by varying the voltage of the light source in accordance with the color of the indication to be displayed. A resistor is interposed in series with the signal lamp and contacts on the signal operating mechanism, or of a repeater relay thereof, shunt out a small or a large portion of the resistor according as the signal is conditioned to display its green or its yellow indication, respectively.

I shall describe one form of apparatus embodying my invention, and shall then point out the novel features thereof in claims.

The accompanying drawing is a diagrammatic view illustrating one form of apparatus embodying my invention.

Referring to the drawing, the reference character S designates a light signal of the searchlight type. The signal comprises an armature 5 mounted to rotate between an intermediate position to which it is biased, and two extreme positions. The armature 5 is controlled by an armature winding 6, and is polarized by the field from a permanent magnet or an electromagnet (not shown) so that when the winding 6 is energized, the armature will rotate to its right-hand or left-hand extreme position according as winding 6 is then supplied with current of normal or reverse polarity, respectively. Attached to armature 5 to rotate therewith are three filters or colored roundels G, R and Y, which are arranged to be disposed in the path of a beam of light projected from an associated lamp L according as the armature 5 occupies its right-hand extreme position, its intermediate position or its left-hand extreme position, respectively. For convenience in illustration, lamp L is represented in the drawing disposed above the associated filters, but it will be readily understood that in practice lamp L will be located directly back of the associated filter, and will have associated therewith a suitable optical system, not shown, for projecting a beam of light from the lamp. The signal indicates "Proceed," "Stop," or "Caution," according as the filter G, R or Y is in front of lamp L when it is lighted. Operatively connected with armature 5 is a circuit controller comprising two movable contact fingers 7 and 8. The movable finger 7 cooperates with a fixed contact 7a to close a contact 7—7a when armature 5 occupies its right-hand extreme position, and with a fixed contact 7b to

close a contact 7-7b when the armature occupies either its intermediate or its left-hand extreme position; while the movable finger 8 cooperates with a fixed contact 8a to close a contact 8-8a when armature 5 occupies its left-hand extreme position, and with a fixed contact 8b to close a contact 8-8b when the armature occupies either its intermediate or its right-hand extreme position. A signal of the type described is disclosed and covered in Letters Patent of the United States No. 1,864,224, granted June 21, 1932, to Wesley B. Wells, for Light signals.

The signal S may be controlled in any suitable manner such as by a polarized control relay CR. The relay CR may be controlled in any suitable manner but since the control of this relay forms no part of my present invention, the control circuits for relay CR have been omitted in order to simplify the drawing. It is deemed sufficient for the purposes of the present description to state that when relay CR is energized and its front neutral contacts 11 and 14 are closed, winding 6 of signal S is supplied with current of normal or reverse polarity according as polar contacts 12 and 13 of the relay occupy their normal or reverse positions, respectively. That is, when relay CR is energized and its polar contacts 12 and 13 occupy their normal or right-hand positions (as viewed in the drawing), winding 6 of signal S is supplied with current of normal polarity over a normal energizing circuit which may be traced from one terminal B of a suitable source of current, such as a battery not shown, through front contact 11, polar contact 12 closed in its right-hand position, winding 6 of signal S, polar contact 13 closed in its right-hand position, and front contact 14 of relay CR to the other terminal C of the same source of current. When the polar contacts of relay CR are shifted to their reverse or left-hand positions and front contacts 11 and 14 are closed, winding 6 is then energized with current of the reverse polarity supplied over an obvious reverse circuit; and when relay CR is deenergized, its front contacts 11 and 14 open to deenergize winding 6.

The lamp L may be constantly lighted, as shown in the drawing, or it may be lighted by any suitable approach control scheme only when an indication is necessary. In either event, the lighting circuit usually includes a resistor 10 in series with the lamp to provide a voltage control means. Ordinarily the resistor value is adjusted for the particular service conditions to be met and has a value constant for all of the indications displayed. This results in a uniform voltage applied to the lamp with a resulting uniform intensity of the source, but does not provide uniformly intense beams of different colors due to the differences in the coefficients of transmission of the differently colored filters.

In accordance with an object of my invention, the differences in intensities of the differently colored beams are compensated for by varying the value of the resistance included in the lighting circuit in accordance with the color of the indication to be projected. As here shown, the resistance value is controlled by means of the contacts of the signal circuit controller. Thus, for example, when winding 6 is supplied with current of normal polarity over its previously traced normal energizing circuit so that armature 5 rotates to its right-hand extreme position wherein contacts 7-7a and 8-8b are closed and filter G is disposed in the path of the beam of

light from lamp L, the lighting circuit then extends from terminal B through circuit controller contacts 8-8b and 7-7a, a portion 10a of resistor 10 and the filament of lamp L to terminal C. When winding 6 is supplied with current of reverse polarity over its reverse energizing circuit, then armature 5 rotates to its left-hand extreme position wherein contacts 8-8a and 7-7b are closed and filter Y is disposed in the path of light from lamp L, which now is energized over a circuit extending from terminal B through contact 8-8a, portions 10a and 10b of resistor 10, and the filament of lamp L to terminal C. When, however, the energizing circuits of winding 6 are open and the winding is deenergized, then armature 5 rotates to its biased intermediate position wherein contacts 7-7b and 8-8b are closed and filter R is interposed in the path of light from lamp L which is now energized over a circuit which excludes resistor 10 and which passes from terminal B through circuit controlling contacts 8-8b and 7-7b, and the filament of lamp L to terminal C. It follows that the value of resistance included in the lighting circuit varies from a low (zero) value through a medium to a large value according as the red, green or yellow filter, respectively, is positioned in the path of the beam of light from lamp L. The intensity of the lamp is therefore automatically varied according to the color of the beam to be projected.

The particular values of the resistance inserted in circuit with lamp L when the green or yellow beams are projected, may be selected to provide compensation for the different coefficients of transmission of the different filters so that the different beams have substantially equal intensities. If desired, however, the resistance values may be selected to provide compensation for the differences in eye response to the different colors so as to provide indications having the same apparent brightness rather than actual brightness. That is, a yellow beam of equal intensity with a red beam might appear brighter due to the superior response of the eyes to yellow color, but by properly selecting the resistance values the actual intensities of the beams may be proportioned to provide equally bright red, yellow and green beams as viewed by a person of normal color sight. In any case, the invention provides means for causing a single source of light to project a plurality of differently colored indications having relative intensities independent of the ratios of the coefficients of transmission of the color filters employed.

Although I have herein shown and described only one form of light signal embodying my invention, it is understood that various changes and modifications may be made therein within the scope of the appended claims without departing from the spirit and scope of my invention.

Having thus described my invention, what I claim is:

1. In combination with a light signal comprising a plurality of differently colored filters having different coefficients of transmission and light emitting means having a single light source for projecting a beam from said source through one or another of said filters, means for selecting the filter through which said beam is projected, and means governed by said last-mentioned means for varying the intensity of said light emitting means according to the color filter selected whereby to provide beams of different colors each having a substantially uniform intensity.

2. In a searchlight signal having a single source of light and a mechanism operative to interpose in the path of the beam from said source one or another of a plurality of differently colored filters each having a different coefficient of transmission, means governed by said mechanism for varying the intensity of said source in accordance with the particular filter interposed in the path of said beam to provide beams having relative intensities independent of the ratios of the said coefficients of transmission of said filters.
3. In a searchlight signal having a single source of light and a mechanism for interposing in the path of the beam projected from said source one or another of a plurality of differently colored filters having different coefficients of transmission, a resistor in series with said light source, and means controlled by said mechanism for varying the effective value of said resistance in series with said source in accordance with the color of the filter interposed in said light beam.
4. In a light signal having a source of light and a mechanism for selectively interposing a red, a green or a yellow filter in the path of the beam from said source, the combination therewith of means controlled by said mechanism for providing a relatively high, a medium, or a relatively low intensity for said source according as said red, green or yellow filter is interposed in said beam respectively.
5. In a light signal having an electric lamp and a mechanism for selectively interposing a red, a green or a yellow filter in the path of the beam from said lamp, the combination therewith of means controlled by said mechanism for interposing a minimum, an intermediate, or a maximum value of resistance in series with said lamp according as said red, green or yellow filter is interposed in said beam respectively.

20

GEORGE R. PFLASTERER.
